CLAIM

The ornamental design for a ribbon and yarn spool holder, as shown and described.

DESCRIPTION

FIG. 1 is a front elevational view of the ribbon and yarn spool holder showing my new design;

FIG. 2 is a rear elevational view thereof;

FIG. 3 is a left side elevational view thereof;

FIG. 4 is a right side elevational view thereof;

FIG. 5 is an enlarged top plan view thereof;

FIG. 6 is an enlarged bottom plan view thereof; and,

FIG. 7 is a partial perspective view thereof, the broken line showing of the table and spool is for illustrative purposes only, and forms no part of the claimed design.

FIG. 1

FIG. 2

*FIG. 3**FIG. 4**FIG. 5**FIG. 6*FIG. 7
